FRITZ ASTHÖWER, OF WITTEN AN DER RUHR, PRUSSIA, ASSIGNOR TO JOSEPH R. VON WESSELY, OF NEW YORK CITY.

Letters Patent No. 78,041, dated May 19, 1868.

IMPROVEMENT IN THE MANUFACTURE OF STEEL.

The Schedule referred to in these Letters Patent and making part of the same.

TO ALL WHOM IT MAY CONCERN:

Be it known that I, FRITZ ASTHÖWER, of Witten an der Ruhr, Westphalia, in the Kingdom of Prussia, have invented a new and improved Method of Manufacturing Steel, of which the following is a full, clear, and exact description, reference being had to the accompanying drawings, which make part of this specification, and in which—

Figure 1 represents a vertical longitudinal section at the line $z z$ of fig. 2, through a furnace adapted for carrying out my improved process, and

Figure 2 a horizontal section through the same at the line $y y$ of fig. 1.

The object of my invention is to produce cast steel of uniform quality in a cheaper way than has heretofore been practised, and to this end my invention consists in a novel method of smelting the materials, to produce the steel, in closed crucibles, in a furnace heated by pit-coal, and so arranged that the contents of the crucibles can readily be inspected during the process, and the crucibles can be removed from or replaced in the furnace at any stage of the process without interrupting the working of the furnace.

In the accompanying drawings, which show a furnace devised by me for carrying out my improved process, A represents a fireplace, constructed in any approved well known way, for the combustion of the pit-coal. The oxygen necessary to support combustion is to be supplied by a suitable blast-apparatus, through flues or tuyeres, as is well understood. The products of combustion escape through a throat, B, into the first crucible-chamber, C, and thence through the passage D to the second crucible or melting-chamber, E, and finally escape through the chimney F. The ratio of the area of the fire-chamber A to the flues B D is such as to secure a uniformly regular combustion under a given pressure of the blast, and the temperature thus generated is sufficient to melt the softest wrought iron.

The crucibles having been first filled with the proper ingredients to produce the required quality of steel, and properly warmed to prevent breakage, are introduced into their respective chambers (by means of long tongs, mounted on rollers or suspended from cranes in the usual way,) through doors H, sliding vertically in ways suspended by cords running over pulleys, and counterbalanced by suitable weights, as usual in such cases. Each crucible is provided with a cover, having an opening in its top, closed by a removable plug, c. Vertical openings in the domes of the chambers are closed by plugs I. As the crucibles are arranged beneath these openings, the workman can at any time remove the plugs I and c, and thus examine the condition of the contents of the crucibles. When their contents are smelted, the crucibles are withdrawn, and placed upon trucks, or suspended from cranes, and removed to the moulds to discharge their contents.

By my process the furnace is kept constantly heated, and one crucible can be inserted as fast as another is withdrawn, without slackening the fires or interrupting the working of the furnace, and the contents of the crucibles can easily be inspected whenever desired.

What I claim as my invention, and desire to secure by Letters Patent, is—

1. The combination of the fire-chamber A and crucible-chambers C, E, as and for the purposes set forth.
2. The construction of the dome of the furnace with vertical plugged openings, as described, to afford a view of the interior.
3. The crucibles, having plugged covers arranged beneath the openings in the dome, as and for the purpose described.

In testimony whereof, I have hereunto subscribed my name.

FRITZ ASTHOWER.
